UNITED STATES PATENT OFFICE.

JAMES W. GRAY, OF TACOMA, WASHINGTON.

LOCK-JOINT FLOORING.

1,201,285.

Specification of Letters Patent. Patented Oct. 17, 1916.

Application filed August 10, 1915. Serial No. 44,740.

To all whom it may concern:

Be it known that I, JAMES W. GRAY, a citizen of the United States, residing at Tacoma, in the county of Pierce, State of Washington, have invented certain new and useful Improvements in Lock-Joint Flooring, of which the following is a specification.

This invention relates to wooden flooring and has especial reference to the shape which contiguous edges of the boards are cut.

The objects of the invention are to provide such a shape as will eliminate the defects in the common tongue-and-groove form at present in use; especially, preventing the vertical sliding and creaking of one board past the adjacent board between the supports, providing a tight joint between said boards even though the boards may shrink apart slightly, allowing for a greater depth of wear in the upper surface of the boards without reducing the strength of the joint, increasing the strength of the joint, providing a form which will not be easily injured when it is being nailed in place, providing a means whereby one board on being fastened down locks the joint between it and the adjacent board against vertical movement, providing a joint which may be put together even though the boards may be slightly swollen by dampness, and providing a shape which itself protects its wearing edges from injury when being shipped. I attain these and other objects by the devices and arrangements illustrated in the accompanying drawings, in which—

Figure 1 is a section on an enlarged scale of a strip of my improved flooring showing it in position in relation to the adjacent board on one side and showing the edges of the next adjacent board on the other side being inserted in place; Fig. 2 is a perspective view showing parts of two boards laid to form a floor; Fig. 3 is a section of one of my improved flooring boards showing the nail passing therethrough and into the supporting joist; Fig. 4 is an end elevation of a floor being laid illustrating how a board which has been slightly swollen is laid; and Fig. 5 is an end elevation showing a number of boards as they are stacked and secured together for shipment.

Similar numerals of reference refer to similar parts throughout the several views.

Referring to the construction illustrated in the drawings:—The top or wearing sur-

face 1 is made of standard width from edge to edge and the lower or bearing surface 2 is slightly narrower. One side of the board is provided with a lip while the other is 60 provided with a corresponding recess. Referring first to the side having the lip, we will follow its course from the wearing surface 1 to the bearing surface 2. This side leaves the surface 1 at a right-angle, as at 65 3, but curves outward on a circular arc 4, forming a concave surface which extends to the end of the lip 5; then it passes vertically downward a short distance, as at 6, thus forming the end of the lip; then it passes 70 inward on a line 7, which is inclined about 3 degrees downward from the horizontal, said line 7 passing inward about twice the distance that the line 6 extends outward from the edge 3, thus undercutting the said 75 edge 3 and forming the tightening under surface of the lip 5; then it passes to the bearing surface 2, preferably following an inclined outward direction, as at 8, so that the lower edge 9 thereof is substantially 80 under the upper edge 3.

Similarly the side having the recess therein leaves the edge 10, opposite to the above mentioned edge 3, of the wearing surface 1 on a convex circular arc 11, leaving said 85 surface 1 at a right-angle therewith, and passes inward on said curved line 11 until it has passed the point corresponding with the junction of the surfaces 4 and 6, above described, and then passes by a reversed 90 curve, as at 12, to join the downwardly inclined outwardly projecting shoulder 13 which corresponds with the above mentioned lower side 7 of the lip 5. The curves 95 4 and 11 are made with equal radii so that when the points 3 and 10 are in contact and the surfaces 1 are in alinement the said surfaces 4 and 11 are also in contact. Also the surface 13 is made at the same angle as the surface 7 so that when they touch they will 100 contact along a wide surface. The shoulder 13 is however very slightly raised relatively to the said line 7 so that the two surfaces 7 and 13 will come in contact with each other before the surfaces 4 and 11 meet (see left-hand of Fig. 1) and also the surface 13 is 105 slightly narrower than the surface 7. Then the surface 14 joins the end of the surface 13 with the side 2, being parallel with but slightly separated from the side 8, above 110 described, and forming an obtuse angle 15 with the said side 2. This angle 15 is almost

under the angle 10 but is very slightly undercut therefrom. The sides 13 and 14 join in an angle 16 and this angle projects outward from the edge 10 a distance substantially equal to the distance that the curve 11 undercuts the said edge 10.

Thus it will be seen that both contiguous sides have outward extensions (the lip 5 and the shoulder 13) extending beyond the line 10 of juncture (3, 10) of the two adjacent boards, that said extensions are in contact with each other along the lines 7 and 13, which are substantially as wide as the present tongue-and-groove construction, but that 15 each said part extends out only one-half its total width and the boards are undercut only one-half the amount of the present groove and that therefore all the parts of the joint are stronger than in the tongue-and-groove construction. The lip 5 extends out only one-half as far as a tongue and it cannot be readily split from the board because its upper surface extends on a curve to the wearing surface 1 of the board, thus 20 forming a root of substantially twice the thickness of the usual tongue, while the undercut side 7 is so slight as to be substantially no weaker than the solid board: the recess overhang at 10 is only one-half the 25 overhang of the parts forming the ordinary groove and the depth is substantially the same, while its shape forms a cantaliver which is as strong as the rectangular form, hence this part is twice as strong as that 30 of the said groove construction. The part from the shoulder line 13 to the bearing surface 2 is thicker and therefore stronger than the lower side forming the groove. Hence 35 all the parts of the said joint are considerably stronger, both under load and in resistance to damage, than the tongue-and-groove joint. Also it must be observed that this board can be cut from about $\frac{1}{4}$ inch less width of stock than the corresponding 40 size of tongue-and-groove construction, thus making a great saving in material there-over.

A floor is laid by first nailing one board down, lip edge out, driving the nails 17 on 45 an inclined line (Fig. 3) through the concave surface 4. Then the shoulder 13 of the next board is inserted under the lip 5 thus nailed. The said shoulder engages the lip before the board is forced home into 50 position (Fig. 1) and then the board is thus forced into position and nailed as above. Now, the slight incline to the surfaces 7 and 13 has been such as to put the parts under strain when the boards are forced 55 into contact at their edges 3 and 10, the shoulder 13 supporting the lip 5 and the surface 4 of the lip 5 supporting the cantaliver 11, so that the joint between the boards is no weaker between supports than are 60 the boards themselves, hence there will be 65

no vertical motion between the boards when loaded between the supports since they are effectually interlocked in tight contact with each other. If the lip 5 or the shoulder 13 should become swollen by dampness before 70 laying, then the new board is inserted by tipping its edge as shown in Fig. 4. If the boards shrink after laying, the joint will be stronger and stiffer than the tongue-and-groove because the surfaces 7 and 13 will 75 remain in contact throughout their length but with slightly less width, so that the lip edge will be supported by the recess edge of the adjacent board, but there will be a slight motion permitted if the greater 80 strain is on the recess edge of the board, though even then the motion will be no greater than occurs in the usual tongue-and-groove boards at present in use.

An additional advantage on my improved 85 boards is found in the fact than when they are bundled, as shown in Fig. 5, the wearing edges 3 and 10, which it is important should be kept in perfect condition, are protected by integral projections, 5 and 16 respectively, which prevent any contact with said edges to damage them. This feature is not found in the tongue-and-groove form since the edge in which the groove is made has no 90 integral projection to protect it from damage.

Although flooring has been mentioned throughout the above description it is to be understood that I do not confine myself to flooring but to any form of boards 100 which are now joined by a tongue-and-groove construction, such as drop-siding, ceiling, silo-boards, etc.

Having described my invention, what I 105 claim as new is:

1. A lock joint for flooring and the like comprising in combination a wooden member having an outwardly and downwardly inclined surface leading from the top surface thereof, said inclined surface being 110 adapted to receive a holding nail, a substantially horizontal surface forming with said inclined surface a projecting lip, said substantially horizontal surface, however being inclined somewhat downwardly and inwardly, a third surface connecting said substantially horizontal surface with the underside of the member, said third surface and said substantially horizontal surface forming 115 a substantial recess beneath said lip, and a second member having surfaces complementary to said first mentioned and said second mentioned surfaces, a recess complementary to said lip, and a lip for projecting into the recess beneath said first mentioned 120 lip, the substantially horizontal surfaces of the two members wedging together to firmly hold the second member against the support, the lip on said second member being of materially less length than the recess in said 125 130

first mentioned member whereby a strong wedging engagement between the substantially horizontal surfaces of the two members is insured.

- 5 2. As an article of manufacture, strips of wood having one side surface formed with an outward concave surface extending from the wearing surface and forming a slightly extending lip; terminating in a narrow 10 vertical surface near the center of the side; the under side of said lip being undercut on a downwardly inclined line extending inward from said vertical surface a distance substantially twice as great as said lip extends 15 from the edge of the wearing surface; the remainder of said side surface extending outward from the inner end of said undercut on an inclined line to the bearing surface of said strip; and having the opposite side surface complementarily formed.

3. A lock joint for flooring and the like comprising in combination a wooden member having an outwardly and downwardly inclined surface leading from the top surface thereof, said inclined surface being adapted to receive a holding nail and forming a slightly extending lip, said lip terminating in a narrow vertical surface near the center of the edge of said member, the 25 underside of said lip being undercut on a downwardly inclined line extending inward from said vertical surface, a third surface extending from the inner end of said undercut to the under side of the member and thus 30 forming a recess beneath said lip, and a second member having surfaces complemental to said first mentioned and said second mentioned surfaces, a recess complemental to said lip, and a lip for projecting into the recess beneath said first mentioned lip, the substantially horizontal surfaces of the two members 35 wedging together to firmly hold the second member against the support, and the lip on said second member being of materially less length than the recess in said first mentioned member whereby a strong wedging engagement is insured irrespective of swelling.

JAMES W. GRAY.

said lip, and said second mentioned member having a lip projecting into said recess but 40 being materially shorter than said recess, whereby a firm wedging engagement is obtained between the two members irrespective of swelling.

4. A lock joint for flooring and the like 45 comprising in combination a wooden member having an outwardly and downwardly inclined surface leading from the top surface thereof, said inclined surface being adapted to receive a holding nail, a substantially horizontal surface forming with said inclined surface a projecting lip, said substantially horizontal surface, however, being inclined somewhat downwardly and inwardly to form a wedging surface, a third 50 surface connecting said substantially horizontal surface near the under side of the member, said third surface and said substantially horizontal surface forming a recess beneath said lip, said substantially horizontal surface extending inwardly a greater 55 distance than said first mentioned surface extends outwardly, and a second member having surfaces complemental to said first mentioned and said second mentioned surfaces, a recess complemental to said lip, and a lip for projecting into the recess beneath said first mentioned lip, the substantially horizontal surfaces of the two members 60 wedging together to firmly hold the second member against the support, and the lip on said second member being of materially less length than the recess in said first mentioned member whereby a strong wedging engagement is insured irrespective of swelling.
